INVENTOR
Daniel J. Murnane
By Charles S. Evans

HIS ATTORNEY

UNITED STATES PATENT OFFICE.

DANIEL J. MURNANE, OF SAN MATEO, CALIFORNIA, ASSIGNOR TO NON-PRESSURE GLAZING COMPANY, OF SAN FRANCISCO, CALIFORNIA, A CORPORATION OF CALIFORNIA.

SASH FOR HOLDING GLASS.

Application filed May 22, 1926. Serial No. 110,875.

My invention relates to metallic window sashes and particularly to division and corner sashes used for holding large and heavy sheets of plate glass.

5 One of the objects of my invention is to provide a sash embodying stiffening means to provide a rigid mounting for the glass such that no strain is produced in the glass. Another object is the provision of a sash 10 structure in which the visible and glass contacting portions comprise a housing of relatively thin material reinforced by a stiffening bar hidden from view within the housing.

My invention possesses other objects and 15 features of advantage some of which with the foregoing will be set forth in the following description of the preferred form of my invention which is illustrated in the drawings accompanying and forming part of this 20 specification. It is to be understood that I do not limit myself to the showing made by said drawings and description, as I may adopt variations of the preferred form within the scope of my invention as set forth in 25 the claims.

In the drawings:

Figure 1 is a horizontal sectional view thru a division sash embodying my invention, and 30 adapted to hold two sheets of glass in planar alignment.

Figure 2 is a side elevation of the tie bar embodied in my invention.

Figure 3 is a horizontal sectional view of 35 a corner sash embodying a modified form of my invention, and adapted to hold two sheets of glass at an angle to each other.

Figure 4 is a vertical sectional view of the 40 stationary member alone, showing the bridge and screw construction of the sash. The plane of section is indicated by the line 4-4 of Figure 1.

Figure 5 is a detail of the adjusting screw.

In terms of broad inclusion the sash of 45 my invention comprises a stationary member having spaced sides made of relatively thin material such as brass or bronze, and between which is rigidly disposed a heavy stiffening bar. The edges of the spaced sides are extended to form flanges adapted to engage 50 one side of the glass. An adjustable member is provided having flanges for engagement with the other side of the glass. Fas-

tening the stationary and the adjustable members together are a plurality of tie bars each interlocked with the adjustable member 55 and extending across the stiffening bar to which they are clamped.

More specifically my invention comprises a stationary member preferably formed of relatively thin metal of U-shaped section, and 60 comprising a casing having spaced sides 2 and 3 which are extended to form flanges 4 and 5 in planar alignment, and against which the glass sheets 6 lie. Interposed between the sides 2 and 3 is a stiffening bar 7. The 65 stiffening bar is held in place by means of spacing sleeves 9 and 11 arranged in pairs near each edge of the stiffening bar and thru which pass tie rods or rivets 12 which firmly secure these members to the spaced sides 2 70 and 3 of the casing, so that the casing is retained rigidly in shape and the flanges 4 and 5 kept in planar alignment.

Formed at intervals on the stiffening bar 7 are a plurality of conical recesses forming 75 seats 13, and over each seat 13, and secured to the stiffening bar, is a bridge 14 provided with a centrally disposed boss 16. A screw 17 is threaded in each of the bosses 16, and on the inner end of the screw is a cupped head 18 80 shaped to form an efficient clamping edge in conjunction with the seat 13.

Coacting with the stationary member and engageable with the other side of the glass is an adjustable member 19 formed with inwardly turned glass engaging flanges 20 and 21. Connecting the adjustable member and the fixed member are a plurality of tie bars 22 each of which is preferably formed of a single piece of metal having a cross piece 23 85 at one end adapted to engage the adjustable member behind the flanges 20 and 21, so as to be interlocked therewith. The other end of the tie bar is provided with corrugations 24 90 so as to make the end deformable, and is 95 adapted to extend over one of the seats 13.

When the sash parts are in assembled position as shown in Figure 1, the heads 18 of the screws 17 clamp the ends of the tie bars 22 to the stiffening bar 7 over the seats 13. Since 100 the ends of the tie bars are deformable, they readily conform to the shape of the seats and are clamped to the bar 7 in exactly the position in which the workman places them with-

out movement caused by the tightening of the screw. If movement of the tie bar occurs with tightening of the screws 17, the glass is either loosely held or submitted to undesired strains. In either case breakage is apt to follow. The cupped edge of the screw engaging the corrugations 24 results only in a clamping pressure exerted in the direction of the axis of the screw, with absolutely no tendency to move the tie bars transversely. The outer ends of the screws 17 are provided with slots 26 to provide means for adjusting the screws, and the side 3 of the stationary member is provided with openings 27 to permit access to the screws.

In Figure 3 I have shown a corner sash embodying a modified form of stiffening bar, and formed to support two sheets of glass 28 at an angle to each other. The edges of the stationary member are extended to form rounded glass engaging flanges 31 and 32 against which the glass sheets may rest at any included angle. The adjustable member 33 is shaped to conform to the angle of the glass, the central curved portion 34 giving wide flexibility in this regard. The stiffening bar 36 is secured near one edge only because of the narrowness of the casing 37. Casing and bar are held in rigid assembly by the tie rods 38 extending thru the spacing sleeves 39.

I claim:

1. A sash for holding glass comprising a stationary member having spaced sides the edges of which are adapted to engage one side of the glass, an adjustable member adapted to engage the other side of the glass, means for operatively connecting said members, and a bar rigidly disposed between the spaced sides of the stationary member to form a stiffening member therefor.
2. A sash for holding glass comprising a stationary member having spaced sides the edges of which are extended to form flanges having faces in planar alignment and adapted to engage one side of the glass, an adjustable member adapted to engage the other side of the glass, means for operatively connecting said members, and a bar rigidly dis-

posed between the spaced sides of the stationary member to maintain the faces of the flanges in planar alignment.

3. A sash for holding glass comprising a stationary member having spaced sides the edges of which are adapted to engage one side of the glass, an adjustable member adapted to engage the other side of the glass, means for operatively connecting said members, a stiffening bar disposed between the spaced sides of the stationary member, spacing means disposed between the bar and the spaced sides, and a tie rod cooperating with the spacing means for rigidly connecting the sides to the bar.

4. A sash for holding glass comprising a stationary member having a pair of spaced sides the edges of which are adapted to engage one side of the glass, an adjustable member adapted to engage the other side of the glass, a stiffening bar rigidly disposed between the spaced sides of the stationary member, a tie bar interlocked with said adjustable member, a bridge member secured to said stiffening bar, and a screw threaded in said bridge member for clamping said tie bar to said stiffening bar.

5. In a sash for holding glass, a member of U-shaped section and formed of relatively thin material and the edges of which are extended to form glass-contacting flanges, a stiffening bar disposed between and parallel to the sides of the member, and means for rigidly connecting the stiffening bar to said member.

6. A sash for holding glass comprising a stationary member having spaced sides the edges of which are adapted to engage one side of the glass, an adjustable member adapted to engage the other side of the glass, means for operatively connecting said members, a stiffening bar interposed between and parallel to the spaced sides of said stationary member, and spacing means disposed between the bar and the spaced sides at each edge of said bar.

In testimony whereof, I have hereunto set my hand.

DANIEL J. MURNANE.
